UNITED STATES PATENT OFFICE.

JOHN JAMES ROYLE, OF MANCHESTER, ENGLAND.

DESIGN FOR A WASH-BASIN.

SPECIFICATION forming part of Design No. 20,908, dated July 7, 1891.

Application filed June 9, 1891. Serial No. 395,714. Term of patent 7 years.

To all whom it may concern:

Be it known that I, JOHN JAMES ROYLE, a subject of the Queen of Great Britain, residing at Manchester, in the county of Lancaster, England, have invented and produced a new and original Design for Wash-Basins, of which the following is a specification.

This design has for its object to provide a novel, ornamental, and characteristic wash-basin which presents a distinguishing appearance; and it consists in a wash-basin having a rectilinear rear edge merging at its extremities into curved or segmental end edges, which extend into the outwardly-curved front edge of the basin.

The design is exhibited by the accompanying drawings, in which—

In the drawings the reference - numeral 1 indicates the rectilinear rear edge running approximately the full length of the basin and merging at its extremities into the curved or segmental end edges 2, which extend into the outwardly-curved front edge 3. The front wall 4 of the basin is arranged at a greater angle of inclination than the rear wall 5, as seen in Fig. 3, and the interior surface 6 is uniformly curved. The bottom wall portion is provided with a horizontal supporting flange or ledge, and the whole constitutes an ornamental, distinguishing, and characteristic appearance.

What I claim is—

The design for a wash-basin, substantially as shown and described.

In testimony whereof I have hereunto set my hand and affixed my seal in presence of two subscribing witnesses.
